US0D1094278S

(12) **United States Design Patent** (10) **Patent No.:** **US D1,094,278 S**
(45) **Date of Patent:** **** Sep. 23, 2025**

(54) **CHARGING PLUG**

(71) Applicant: **Guangfu Yang**, Suining (CN)

(72) Inventor: **Guangfu Yang**, Suining (CN)

(73) Assignee: **Guangfu Yang**, Suining (CN)

(**) Term: **15 Years**

(21) Appl. No.: **29/992,299**

(22) Filed: **Mar. 7, 2025**

(51) **LOC (15) Cl.** **13-02**

(52) **U.S. Cl.**

USPC **D13/107**

(57) **CLAIM**

The ornamental design for a charging plug, as shown and described.

DESCRIPTION

FIG. 1 is a front perspective view of a charging plug, showing my new design.

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the charging plug that form no part of the claimed design.

1 Claim, 8 Drawing Sheets
